(57) **CLAIM**

The ornamental design for a shower head dial ring, as shown and described.

DESCRIPTION

FIG. 1 is a perspective view of a shower head dial ring showing my new design, portions shown in broken lines forming no part of the invention;

FIG. 2 is a left side view thereof, the right side, top and

bottom views being a mirror image of the left side;

FIG. 3 is a front view thereof; and,

FIG. 4 is a rear view thereof.
